DESIGN FOR AN ENVELOPE.

Design No. 13,818, dated March 27, 1883.

UNITED STATES PATENT OFFICE.

GIOVANNI SIECKENBERGER, OF NEW YORK, N. Y., ASSIGNOR OF ONE-HALF
TO BRADLEY A. HARD AND SAMUEL PARSONS, OF SAME PLACE.

DESIGN FOR AN ENVELOPE.

SPECIFICATION forming part of Design No. 13,818, dated March 27, 1883.

Application filed February 14, 1883. Term of patent 7 years.

To all whom it may concern:

Be it known that I, GIOVANNI SIECKENBERGER, of New York, in the county and State of New York, have invented a new and original Design for Envelopes, of which the following is a specification.

In the accompanying photographs, Figure 1 represents a face view of the envelope-blank before it is folded into a complete envelope.

10 Fig. 2 is a back view of the folded envelope.

This invention relates to a new manner of ornamenting envelopes; and it consists in applying to each flap thereof serrated irregular borders; also, in ornamenting the face thereof with irregular blots or spots, as hereinafter more fully specified.

In the photographs, the letter A represents the blank for the envelope. a is the face of the envelope, and b d e f are the flaps thereof.

20 Each of the flaps carries on its exposed side a border, g, of irregular outline, the borders on the flaps d and f being at such a distance from the edges of the flaps as to come in contact with the borders on the other flaps, b and e,

when the envelope is folded, as in Fig. 2, thus 25 producing in the complete envelope the peculiar effect shown in Fig. 2—namely, of a cross-like figure on a back of the envelope with irregular outline. On the face a of the envelope are blots or spots h, of irregular outline. 30

I claim—

1. The design for an envelope having flaps b d e f, the same consisting of borders g, of irregular outline, placed on said respective flaps, substantially as shown. 35

2. The design for an envelope, the same consisting of a cross-like figure on the back thereof, said cross-like figure having irregular outline, substantially as shown.

3. The design for an envelope, the same consisting of the blots or spots h on the face of the envelope, substantially as shown. 40

This specification of my invention signed by me this 12th day of February, 1883.

GIOVANNI SIECKENBERGER.
